LIQUID SURFACE COOLER

Arthur F. Pinto, Berkeley, Calif.

Application November 9, 1948, Serial No. 59,172

4 Claims. (Cl. 62—141)

1

This invention relates to surface coolers and to means for cooling liquids by the action of such coolers upon the surface of the liquids.

There are a number of instances wherein it is necessary or desirable to avoid volatilization of a liquid from a body, a particular one with which I am concerned being the trituration of an oil-containing material in a low boiling point solvent for the extraction of the oil. In the process of trituration, involving comminution and vigorous agitation, the mixture becomes progressively warmer and finally the solvent escapes and fills the room before the operation is complete, unless some method to prevent this is employed. Since a cooler within the liquid would interfere with the operation and a cooler above the surface of the liquid would not condense the vapors sufficiently to prevent their escape, I have developed a means for surface-cooling a liquid. Further, this apparatus for cooling is thoroughly satisfactory because heat tends to rise to the surface and, therefore, the surface is the point where a cooler is most effective.

It is an object of my invention to provide an efficient device for cooling a liquid body by the action of a cooler upon the surface of the liquid.

Another object is to provide a means for controlling the temperature of the surface of a liquid body so as to minimize evaporation therefrom.

In the drawing,

Figure 1 shows a representative form of apparatus in connection with a specific use.

Figure 2 is a fragmentary view showing a modified form of cooler.

In the drawing, the reference numeral 1 refers to a ring stand of the ordinary style found in laboratories. Reference numeral 2 refers to a common type of mixer or stirring apparatus, the container 3 of which has in its bottom comminuting blades 4 driven by a motor in the base.

Adjustably supported on the upright of the ring stand by means of clamp 5 is a suitable form of surface cooler for use in this particular operation. The cooler is referred to generally by the reference numeral 10. It has a bulbous lower portion 11 and refrigerant inlet and outlet tubes 12 and 13 respectively. Inlet tube 12 extends substantially to the bottom of the bulbous portion so that the incoming liquid will have the greatest effect.

In order to cool the surface of the liquid under treatment, it is contemplated that the cooler 10 will be adjusted into the surface of the liquid, as shown in Figure 1, and that cooling will

2

be accomplished by absorbing heat conducted from the surface of the liquid. The refrigerant may be a salt solution, an expanding gas such as ammonia, CO₂, or other well known refrigerant, or in some instances merely cool tap water. In the particular operation in connection with which I have described this device, I employed a solvent having a boiling range of from 34° to 60° C. The solvent was used for the purpose of extracting oil from chopped copra. Without cooling, so much of the solvent evaporated as to interfere with the trituration and healthful condition of the air in the room. It was impractical to jacket the vessel 3 and a cooler within the liquid interfered with the circulation set up by the blades 4. By employing the device shown and circulating therethrough cold tap water, evaporation of the solvent from the surface of the body of the liquid was prevented, and this without any interference with the trituration.

It should be understood that it is not contemplated that the surface cooler 10 be operated in such a fashion as merely to condense vapors which are allowed to form from the liquid, but that the surface layer of the liquid and liquid itself is to be cooled below a temperature at which excessive vaporization occurs. The heat is absorbed from the liquid primarily by conduction rather than by radiation. Any liquid may be cooled, and the cooling may be extended to actual freezing.

For use in connection with a more common type of stirrer in which the rod depends from the motor and enters the top of the vessel (corresponding to the vessel 3), I have developed a cooler substantially like that shown in Figure 1 but having a central tube for passage of the rod. This modification is shown in Figure 2.

40 The cooler is otherwise like that shown in Figure 1, but has additionally a tube 22 from end to end through which the shaft or rod 41 of a common type of mixer 40 is accommodated. In all respects it will be used as has been above described.

45 The forms of the apparatus shown in the drawing are very suitable for the particular operation described. Where, however, the surface of the liquid is larger, different forms of the cooler are employed.

Preferred materials are the metals least subject to corrosion and which are good heat conductors. Tubes 12 and 13 are preferably made integral with the cooler, as will be tube 22. Details are, of course, subject to change.

I claim:

1. In combination, a vessel having an open upper end, a plurality of cutting blades adapted to be rotated adjacent the bottom of said vessel to cut material in the vessel adjacent to said bottom and to agitate and to force upwardly a fluid in the vessel; means for cooling fluid in the vessel and for reducing contact of the agitated fluid with the atmosphere comprising a bulb adapted to be positioned in contact with the upper surface of the fluid in the vessel and of a size to close substantially completely the otherwise open end of the vessel, means for circulating a cooling medium through the bulb to cool the bulb and the fluid in the vessel which is in contact with the bulb, and means supporting said bulb in the vessel in a vertically spaced relation above said bottom and said cutting blades and in contact with only the upper liquid surface level in the vessel.

2. In combination, a vessel having a bottom and an open top, a shaft rotatably mounted in said bottom and extending therethrough to just above and adjacent said bottom, a base engaged with said bottom and supporting said vessel in a superimposed position, a motor in said base for rotating said shaft, a plurality of material comminuting blades secured on that end of said shaft which is above but which is adjacent said bottom to comminute material in the vessel in a region adjacent the bottom of the vessel and at a first elevation, a bulb of a size to fit within said vessel and having an area sufficient in a horizontal plane to close substantially said open top, means for circulating a refrigerant through said bulb, and means supporting the bulb adjustably with respect to the top of said vessel and positioning the bulb in the vessel at a level whereat an exposed liquid surface in the vessel is at a minimum during rotation of the material comminuting blades.

3. In combination, a vessel having a bottom and an open top, a shaft rotatably mounted and extending to adjacent said bottom, a motor for rotating said shaft, a plurality of material comminuting blades secured on that end of said shaft which is above but which is adjacent said bottom

to comminute material in the vessel in a region adjacent the bottom of the vessel and at a first elevation, a bulb of a size to fit within said vessel and having an area sufficient in a horizontal plane to close substantially said open top, means for circulating a refrigerant through said bulb, and means supporting the bulb adjustably with respect to the top of said vessel to position the bulb in the vessel in a spaced relation to said blades and wherein the bulb is spaced from the blades at a level whereat an exposed liquid surface in the vessel is at a minimum during rotation of the material comminuting blades.

4. In combination, a vessel having a bottom and an open top, a shaft rotatably mounted and extending to adjacent said bottom, a motor for rotating said shaft, a plurality of material comminuting blades secured on that end of said shaft which is above but which is adjacent said bottom to comminute material in the vessel in a region adjacent the bottom of the vessel and at a first elevation, a hollow vessel closure of a size to fit within said vessel and having an area sufficient in a horizontal plane to close substantially said open top, means for circulating a refrigerant through said hollow vessel closure, and means supporting the hollow vessel closure adjustably with respect to the top and the bottom of said vessel and enabling the hollow vessel closure to be positioned in the vessel in a spaced relation to the blades and at a level whereat an exposed liquid surface in the vessel is at a minimum during rotation of the material comminuting blades.

ARTHUR F. PINTO.
